UNITED STATES PATENT OFFICE.

ARCHIBALD DAVID MACDONALD, OF SOUTH YARRA, VICTORIA, AUSTRALIA.

AERIAL PROPELLER.

1,095,649.

Specification of Letters Patent.

Patented May 5, 1914.

Application filed January 16, 1912. Serial No. 671,479.

To all whom it may concern:

Be it known that I, ARCHIBALD DAVID MACDONALD, a subject of the King of Great Britain, residing at Britannia House, Toorak Road, South Yarra, in the State of Victoria, Australia, have invented certain new and useful Improvements in Aerial Propellers; and I do declare the following to be a full, clear, and exact description of the invention, such as will enable others skilled in the art to which it appertains to make and use the same.

This invention has been devised to provide means for propelling aeroplanes, dirigible aerial machines and the like aerial vehicles.

In order that the invention may be the more easily understood, reference may be made to the accompanying drawings, in which—

Figure 1 is a front view of apparatus embodying my invention. Fig. 2, a side elevation thereof in longitudinal section taken at line 1—2 on Fig. 1. Fig. 3 is a front view of the internal or moving portion of Fig. 1 and omitting the outer drum, while Fig. 4 illustrates one form of arrangement of my invention when applied to an aerial machine. Fig. 5 is a front view of the forward end of the drum showing a Venetian blind secured therein with the slats in a closed position. Fig. 6 is a section on the broken line 1—2 of Fig. 5, and Fig. 7 is a diagrammatic illustration in perspective of the manner of connecting the cords by which the Venetian blind is operated.

In these drawings it will be seen that in lieu of employing an ordinary propeller revolving or rotating in the open air and driven by a motor I communicate the motive power from such engine to a spindle *a* on which are set several (preferably four) radial arms *b*; these arms are at the front and back ends of the spindle *a* and preferably close to the bearings in which the said spindle runs.

Running from each of the front radial members or arms *b* to its corresponding back one is a vane *d* having a depth the equivalent of the length of the front radial arm *b* and vanishing to a point at the outer diameter of the back radial arm at *d'*, the top longitudinal line *d²* of each of the said vanes *d* being at right-angles to the said arms *b* but the lower edge *d³* being cut away to form the said vane into an extended tri-

angle. These vanes *d* may be either flat as one plane or in some cases the tapering or narrowing end *d'* may curve in accordance with any predetermined scheme of clearance for the air which the vane when revolving will draw in at *e* and eject at *f*.

The ends of the radial arms *b* are stayed to one another and also to the central spindle *a* by straining wires or rods *g* so as to form a rigid construction on the part of the spindle *a* the arms *b* and the vanes *d*.

The whole longitudinal construction of spindle arms and vanes lies centrally placed within an inclosing cylindrical casing or drum *h* smooth on the interior but braced on the exterior. One or both ends of the drum *h* are open to admit the ingress and egress of air, the amount of opening of each end, particularly that of the front, being adjustable by any conveniently designed closing in devices, one of which latter may consist of Venetian or louvered shutters, such as illustrated in Figs. 5 and 6, their adjustment being operable by the driver at his place in the machine, the whole being so arranged that on the driver closing the openings the vanes *d* will cease to have propulsive effect owing to their want of air on which to operate, and it will therefore be also noted that the adjustment of speed of the aerial machine can be controlled by the driver without stopping the engine as would be necessary were the open propeller system to be used.

To the drum is attached the supporting planes *i* and floor *j* for human beings, and in some cases the bearings *c* of the spindle may also be mounted upon cross members *c'* from the said drum *h* so that the spindle *a* with its arms and vanes may revolve freely in the said drum. *k* is a pulley for imparting rotary motion to the spindle *a*.

I would have it understood that I do not arbitrarily confine myself to any particular angle nor length of the vanes *d*, nor to the diameter of the arms *b*, spindle *a* and drum *h* as the same may be adjusted to suit the varying requirements of the machines to which my means of propulsion may be employed.

Referring to Figs. 5, 6 and 7, *l* indicates the slats of a Venetian blind. These slats are attached to tubes *m* fixed on spindles *n* operating in bearings at the sides of the drum *h* and the vertical member *c'*. The slats are opened or closed by means of the

cords *o* attached to front and rear levers *p* secured to the tubes *m*. The cords pass through the bottom of the drum under pulleys *r* two of which are at the front and 5 two at the rear of the shutters.

There are two pairs of the cords *o*, one pair connected to the levers *p* at the front, and the other pair to the levers *p* at the rear; each pair of cords *o* are preferably 10 connected to a separate cord *o'*, which cords *o'* extend to within reach of the operator which enables him to open or close all the slats of the Venetian blind at the same time, according to which one of the cords *o'* is 15 manipulated.

I claim as my invention:

1. An aerial propeller comprising a cylindrical casing, a central longitudinal shaft within said casing, rigidly flat triangular blades radiating from said shaft, each of 20 said blades having its forward end extending throughout the entire length of the radius and diminishing in width to a vanishing point at the rear. 25 2. An aerial propeller comprising a cylindrical casing, a central longitudinal shaft within said casing, rigidly flat triangular blades radiating from said shaft, each of 30 said blades having its forward end extending throughout the entire length of the radius and diminishing in width to a vanishing point at the rear, and radial arms secured to said shaft and to which the rear ends of the blades are attached, said radial 35 arms having a length approximately equal to the length of the forward ends of the blades.

3. An aerial propeller comprising a cylindrical casing, a central longitudinal shaft 40 within said casing, radial arms adjacent each end of said shaft and secured thereto, and rigidly flat triangular blades extending between said arms and connected thereto at each end, the forward ends of said blades 45 having a length approximately equal to the length of the forward arms and extending rearwardly to a vanishing point.

4. An aerial propeller comprising a cylindrical casing, a central longitudinal shaft 50 within said casing, radial arms adjacent each end of said shaft and secured thereto, rigidly flat triangular blades extending between said arms and connected thereto at

each end, the forward ends of said blades having a length approximately equal to the 55 length of the forward arms and extending rearwardly to a vanishing point, and means for regulating the supply of air to the blades.

5. An aerial propeller comprising a cylindrical casing, a central longitudinal shaft within said casing, radial arms adjacent each end of said shaft and secured thereto, rigidly flat triangular blades extending between 60 said arms and connected thereto at 65 each end, the forward ends of said blades having a length approximately equal to the length of the forward arms and extending rearwardly to a vanishing point, and adjustable shutters for regulating the supply of 70 air to the blades.

6. An aerial propeller comprising a cylindrical casing, a central longitudinal shaft within said casing, radial arms adjacent each end of said shaft and secured thereto, 75 rigidly flat triangular blades extending between said arms and connected thereto at each end, the forward ends of said blades having a length approximately equal to the length of the forward arms and extending 80 rearwardly to a vanishing point, adjustable shutters for regulating the supply of air to the blades, and means for operating the shutters.

7. In an aeroplane provided with supporting planes and a platform for a motor and passengers, the combination of a cylindrical casing arranged between the supporting planes and the platform and secured to both, a central longitudinal shaft within 90 said casing, radial arms adjacent each end of said shaft and secured thereto, and rigidly flat triangular blades extending between said arms and connected thereto at each end, the forward ends of said blades 95 having a length approximately equal to the length of the forward arms and extending rearwardly to a vanishing point.

In testimony whereof I have signed my name to this specification in the presence of 100 two subscribing witnesses.

ARCHIBALD DAVID MACDONALD.
